[76] Inventor: **Gaylen E. Hinkeldey**, 69100 Garner,
Cathedral City, Calif. 92234

Primary Examiner—Wallace R. Burke

Assistant Examiner—Marcus Jackson

Attorney, Agent, or Firm—Timmons & Kelly

[**] Term: **14 Years**

[57] CLAIM

The ornamental design for a clear card for X-ray film identification, as shown and described.

DESCRIPTION

FIG. 1 is a perspective view of a clear card for X-ray film identification showing my new design with the broken lines shown for illustrative purposes only and forming no part of the claimed design;

FIG. 2 is a front elevation thereof;

FIG. 3 is a rear elevation thereof;

FIG. 4 is a right side elevation thereof, the opposite side being identical to the view shown;

FIG. 5 is a top plan view thereof; and,

FIG. 6 is a bottom plan view thereof.
